UNITED STATES PATENT OFFICE.

LOUIS EVERETT HASTINGS, OF CHICAGO, ILLINOIS.

CLOTHES-DRIER.

SPECIFICATION forming part of Letters Patent No. 328,484, dated October 20, 1885.

Application filed May 27, 1885. Serial No. 166,837. (No model.)

To all whom it may concern:

Be it known that I, LOUIS E. HASTINGS, a citizen of the United States, residing at Chicago, in the county of Cook and State of Illinois, have invented a new and useful Improvement in Clothes-Driers, of which the following is a specification, reference being had to the accompanying drawings.

This invention relates to clothes-driers; and it has for its object to provide a simple, convenient, and useful article of this character for household use, which can be attached to the wall in a moment's time, on which to hang clothes after being ironed, or small articles to dry, and which can be folded against the wall when not in use, so as to be out of the way.

With these ends in view the said invention consists in the peculiar construction and novel combination of parts, as will be hereinafter set forth, and particularly pointed out in the claims.

In the accompanying drawings, Figure 1 is a perspective view showing my improved clothes-drier applied to the wall of a room, a number of the arms being extended in position for use while the others hang down out of the way. Fig. 2 is a plan view of the drier-frame detached from the wall. Fig. 3 is a longitudinal vertical section of the same. Fig. 4 is a side elevation of one of the drier-arms.

Like letters are used to indicate corresponding parts in the several figures.

Referring to the drawings, A designates a semicircular plate provided around its periphery with an upwardly-projecting rim, C, semicircular in form to correspond with the base-plate A, and having a series of equidistant slots or openings, a, to provide intermediate posts, ribs, or standards, B, corresponding in number to the openings a. From the lower ends of the uprights or posts B extend a corresponding number of radial arms, D, separated by radial slots E, the outer ends of the arms D being connected by a semicircular outer rim, F. The inner end of the plate A is flanged, as at b, and from this flange depend a series of arms, G G' G². Nails, screws, or any suitable fastening means may be driven into the wall in the space between these arms, so as to hold the drier in position, and yet allow its detachment at will, without the necessity of withdrawing the nails. The outer

periphery of the plate A is notched at d to receive the end of the drier-arm, which is adapted to fit snugly therein.

55

H H designate the drier-arms, which are constructed of wood or other suitable material, of any desirable length, the inner ends of the arms being notched or cut out on the under sides, as at e, the outer wall of the notch being straight and the inner wall, e', beveled or dovetailed for the purpose presently described. When the drier-arms are fitted in place, their inner ends abut against the periphery of the plate A, and are received within the notches d, the opening a, between the posts B, receiving the inner end of the drier-arms. The outer rim, F, is notched on its upper face, as at g, to correspond with the slots E, between the arms D, and this notch receives the upper wall of the notch e in the drier-arms when the latter are in position for use.

The plate A, with the short posts B, inner rim, C, arms D, and outer rim, F, is cast in one piece of metal, as will be readily understood. In this manner I am enabled to simplify the construction of parts, provide a more secure connection, and reduce the cost of the drier in manufacturing.

The operation of my invention will be readily understood from the foregoing description, taken in connection with the drawings.

In applying the drier in position, nails or other suitable fastening means are driven into the wall and the arms G G' G² inserted between the nails, this connection being found sufficient to hold the drier in place and allow its detachment at will. By this arrangement I avoid the necessity of withdrawing the fastening means when it is desired to detach the drier from the wall.

When inserting the drier-arms they are raised to a position parallel with the drier frame or bracket, the notch e allowing the insertion on the inner end of the arm over the outer rim, F, and into the radial slots E. While in this position the arms are pushed inward, so as to cause them to work through the openings a, which separate the posts B, and enter the notches d, which are provided at intervals around the periphery of the plate A. When in proper position, the inner ends of the arms fit within the notches d, between the posts B and below the rim C, and in this

manner the arms are held from downward or sidewise movement.

The notch *g* in the outer rim, *F*, receives the upper wall of the notch *e*, provided in the drier-arms *H*. Without this notch *g* the drier-arms would move laterally when in use, and this would be found highly objectionable to those having occasion to use the drier; but by this connection of the drier-arm to the outer rim, *F*, combined with the peculiar connection with the inner rim and the adjacent parts, said arms *H* cannot possibly move either downward or laterally, but are capable of moving outwardly and downwardly when it is desired 15 to fold the drier-arms out of the way. By drawing the arms *H* outward, the upper wall of the notch *e* is caused to travel through the notch *g* of the outer rim, and when the inclined wall *e'* of this notch is reached, the arms 20 swing down automatically, as shown, said arms being held in that position by the inclined wall *e'* being received within the notches *g*.

To hold the arms *H* when in their folded position, I propose to use a swinging hook or 25 catch, *I*, which is pivoted to the inner end of the arms, extends across the open portion of the notch *e*, and engages with a stud, *i*, and by this means the arm cannot drop off the outer rim, *F*, while they are hanging down therefrom. In place of this catch I may employ a 30 short bar to extend across only a portion of the notch to hold the arms in place.

I do not wish to limit myself to the use of any number of drier-arms or any particular 35 shape or construction thereof, as it will be apparent that such may be changed at will without departing from the spirit of my invention.

By my improvement I provide an article of 40 great convenience in the house, for when it is in use it may be attached to the wall and take up but very little room, and when not in use the drier-arms can be readily folded out of the way, or be detached from the drier frame or bracket, and put away until it is desired to 45 again use the drier.

I do not wish to be understood as laying any broad claim to a drier operating on this principle, as such is not my invention. What I do claim is the peculiar construction of the drier

frame or bracket cast with its several parts in 50 one piece in connection with the peculiar attachment of the arms to the bracket, whereby I provide a simple and convenient article of this character, which will be sufficiently strong for the purposes intended.

Having described my invention, I claim—

1. The combination, with the bracket or frame *A*, the vertical posts *B*, radial arms *D*, extending from the posts and having the slots *E*, the outer rim, *F*, connecting the arms *D*, and 60 having notches *g* communicating with the radial slots *E*, of the drier-arms having the notch *e* to fit the rim *F*, the inner ends of the said drier-arms fitting between the posts *B*, and the upper wall of the notch *e* engaging the 65 notch *g*, substantially as described.

2. In a clothes-drier, the herein-described bracket or frame comprising the plate, the upwardly-projecting posts *B*, separated from each other by intervening openings, *a*, and 70 having the notches *d*, the rim *C*, connecting the upper ends of the posts *B*, radial arms *D*, projecting from the posts at their lower ends and separated by intervening radial slots *E*, communicating with the openings *a*, and an 75 outer rim, *F*, having notches *g* in communication with the slots *E*, all of said parts being formed or cast in one piece, in combination with the drier-arms having the notch *e*, which 80 engages the notch *g* of the rim when the rear end of the arm is fitted between the posts *B* and is in its horizontal extended position, substantially as described.

3. The combination, with the bracket comprising the plate *A*, the radial arms *D*, and the 85 outer rim, *F*, the latter being provided with notches *g*, of the drier-arms provided with notches *e*, one wall of which is inclined, and a hook-catch or equivalent device for closing the open portion of the notch *e*, as set forth.

In testimony that I claim the foregoing as my own I have hereto affixed my signature in presence of two witnesses.

LOUIS EVERETT HASTINGS.
